Primary Examiner—T. Chase Nelson*Assistant Examiner*—Karen Acker(74) *Attorney, Agent, or Firm*—Donald E. Hasse; Hasse & Nesbitt LLC(57) **CLAIM**

The ornamental design for a carton, as shown and described.

DESCRIPTION

FIG. 1 is a top perspective view of the carton.

FIG. 2 is a bottom perspective view of the carton.

FIG. 3 is a front elevational view of the carton.

FIG. 4 is a back elevational view of the carton.

FIG. 5 is a left side elevational view of the carton.

FIG. 6 is a right side elevational view of the carton.

FIG. 7 is a top plan view of the carton.

FIG. 8 is a bottom plan view of the carton; and,

FIG. 9 is a sectional plan view of the carton taken along line 9—9 of FIG. 1.

The broken lines in the drawings represent unclaimed parts of the design included for the purpose of showing the design in a position of use and form no part of the claimed design.
